(57) **CLAIM**

The ornamental design for a security device, as shown.

DESCRIPTION

FIG. 1 is a first perspective view of one embodiment of a security device showing our new design;

FIG. 2 is a second perspective view thereof;

FIG. 3 is a top view thereof;

FIG. 4 is a front view thereof;

FIG. 5 is a side view thereof;

FIG. 6 is a back view thereof;

FIG. 7 is a bottom view thereof;

FIG. 8 is a top perspective view of the security device shown in FIG. 1 with the cover shown removed for completeness of illustration;

FIG. 9 is bottom perspective view of the security device shown in FIG. 8;

FIG. 10 is a top view of the security device shown in FIG. 8;

FIG. 11 is a front view of the security device shown in FIG. 8;

FIG. 12 is a side view of the security device shown in FIG. 8;

FIG. 13 is a back view of the security device shown in FIG. 8; and,

FIG. 14 is a bottom view of the security device shown in FIG. 8.
